(57) **CLAIM**

The ornamental design for a sonic teeth cleaner body, as shown and described.

DESCRIPTION

FIG. 1 is a top front perspective view of a sonic teeth cleaner body;

FIG. 2 is a front view of the design;

FIG. 3 is a rear view of the design;

FIG. 4 is a side view of the design;

FIG. 5 is a side view of the design;

FIG. 6 is a top view of the design; and,

FIG. 7 is a bottom view of the design.

In the drawings, the broken lines depict environmental subject matter only and form no part of the claimed design.
